UNITED STATES PATENT OFFICE.

RICHARD G. KIRCHNER, OF DETROIT, MICHIGAN.

MAGNETO-GENERATOR.

1,108,872. Specification of Letters Patent. Patented Aug. 25, 1914.

Application filed March 8, 1913. Serial No. 752,830.

To all whom it may concern:

Be it known that I, RICHARD G. KIRCHNER, a citizen of the United States of America, residing at Detroit, in the county of Wayne and State of Michigan, have invented certain new and useful Improvements in Magneto-Generators, of which the following is a specification, reference being had thereto to the accompanying drawings.

This invention relates to an electric generator of the magneto type especially for ignition systems of internal combustion motors, the device being arranged to form a unit structure without sliding contacts, or the like, which can be used readily for power plants, of automobiles, motor boats, aeroplanes etc. The invention consists of the matters hereinafter set forth and pointed out in the appended claims.

In the drawings, Figure 1 is a view in longitudinal section through a mechanism that embodies features of the invention, together with a diagram showing the sparking terminals of a motor and the circuits thereof, a circuit breaker being also indicated removed from the shaft of the generator and illustrated as in end elevation; and Figs. 2 and 3 are views in detail of a distributor.

As herein shown in preferred form permanent magnets 1 of approved type and design on the base 2 have an armature 3 journaled to rotate in operative proximity to the poles of the magnets. One journal 4 of the armature shaft which conveniently may be hollow, has an insulating bushing 5 in which a hollow extension 6 of the armature is supported, the outer end portion 7 of the latter being carried in a suitable bracket 8. A low tension coil 9 on the armature is in series with a coil 10 wound around the extension 6 to rotate in the bore of a spool 11 on which a secondary high tension coil 12 is wrapped. One terminal 13 of the coils 9 and 10 extends through a suitable insulating bushing to a trip 15 that is mounted in insulated relation on an arm 16 which is grounded on the portion 7 of the armature shaft. A contact point 17 on the trip 15 normally abuts a pin 18 on the arm 16 through the influence of a suitably disposed spring 19 except when a cam roll 20 on the arm 15 is moved inwardly by contact with cam tracks 21 mounted in a suitable casing 22 on the base.

To increase the effect of the positive make and break motion of the trip, a condenser is

placed in shunt with the contacts 17 and 18. Conveniently, this condenser is made of alternating series of disks indicated at 23, of suitable material mounted in insulated relation in a casing or drum 24 which is secured to turn with the shaft extension 5. A suitable conductor as shown at 25 and 26, connects each set of disks with a terminal of the magneto coil and extension. One terminal 27 of the high tension or secondary coil is grounded on the machine while the other 28 is connected with the binding post 29 or the like of an annular terminal 30 that is mounted on the bracket 8 in insulated relation to and concentric with a countershaft 31. Spark plugs 32 of the motor to which the device is applied, are each suitably connected as indicated with the binding posts 33 or the like of segmental terminals 34, disposed in spaced and insulated relation to each other and to the terminal 30, concentrically with the countershaft 31, a casing 35 of suitable design and material forming a support and housing therefor. A pinion 36 on the armature shaft extension and gear 37 on the countershaft 31 or other like positive means, rotate the countershaft in timed relation to the motor shaft and to the magneto shaft. A disk 38 of insulating material is carried by the countershaft 31 to turn between the terminals 30 and 34, an aperture 39 through the disk permitting the secondary circuit to be closed across the air gap thus formed between the annular and segmental terminals in succession. Any suitable means may be provided for shifting the position of the segmental terminals angularly in relation to the movement of the magneto for the purpose of advancing the spark although such means are not shown herein and do not *per se* form a part of the invention.

In operation the induced primary current of the armature through the armature coil and extension is sharply broken periodically by the make-and-break-mechanism, thereby producing the necessary inductive effect in the secondary coil. The distributor periodically closes the secondary circuit to produce the necessary spark at the ignition terminals of the motor in proper relation to the movement of the magneto.

As the generator has no commutator or sliding contacts it is readily maintained in operative condition, as it is free from the necessity of adjustments attendant upon

such sliding contacts and from the constant renewals to which these are subject.

Obviously, changes in the details of construction may be made without departing from the spirit of my invention and I do not care to limit myself to any particular form or arrangement of parts.

What I claim is:—

1. The combination in a magneto generator, with an armature coil having an extension coil in series therewith, of a circuit breaker operatively connected to the magneto in series with the armature coil, and a condenser turning with the armature coil in shunt across the circuit breaker.
2. The combination in a magneto generator, with an armature shaft, an armature coil thereon, an extension mounted on the shaft, a coil in series with the armature coil, a condenser secured on the shaft, and a circuit breaker mounted on the shaft across which the condenser is in shunt, and an interrupter in series with the secondary coil.
3. In a magneto generator, a rotatable armature shaft, an armature coil thereon, an extension mounted on the shaft, a coil in series with the armature coil, a circuit breaker mounted on the shaft in series with the coils, a condenser mounted on the shaft in shunt across the circuit breaker, a high tension secondary coil in inductive relation to the extension coil, and an interrupter in series with the secondary coil operated by the shaft.
4. In a magneto generator, permanent field magnets, an armature shaft rotatable between the pole pieces of the field magnets,

an armature coil on the shaft between the field magnets, a coil on the shaft forming an extension in series with the armature coil, a circuit breaker mounted on the shaft in series with the coils, a condenser mounted on the shaft connected across the circuit breaker, a fixed secondary coil within which the extension coil revolves, and an interrupter in series with the secondary coil.

5. In a magneto generator, permanent field magnets, an armature shaft journaled between the pole pieces thereon, an armature coil on the shaft between the pole pieces, a hollow extension secured to the shaft, a core secured in the extension, a coil mounted on the extension in series with the armature coil, a condenser mounted on the extension in parallel with the coils, a circuit breaker mounted on the extension in series with the coils, a stationary secondary coil concentric with the extension coil, and an interrupter in series with the secondary coil.

6. In a magneto-generator, having an armature coil and an extension coil in series with the armature coil, arranged to rotate in unison therewith, a circuit breaker operatively connected in series with the armature coil, and a condenser in shunt across the circuit breaker adapted to rotate in unison with the armature coil.

In testimony whereof I affix my signature in presence of two witnesses.

RICHARD G. KIRCHNER.
